(57) **CLAIM**

The ornamental design of a top for a beverage bottle insulator, as shown and described.

DESCRIPTION

FIG. 1 is a perspective view from above the top of our top for a beverage bottle insulator design;

FIG. 2 is a side elevation of our top for a beverage bottle insulator design, it being understood that the diametrically opposite side is substantially identical to this figure;

FIG. 3 is a side elevation of our top for a beverage bottle insulator design taken at approximately 90° to FIG. 2, it being understood that the diametrically opposite side is substantially identical to this figure; and,

FIG. 4 is a plan view of our top for a beverage bottle insulator design.

It is to be understood that the bottom of our top for a beverage bottle insulator design is plain and unornamented. The broken lines showing a bottle underneath the claimed design are for illustrative purposes only and form no part of the claimed design. The dashed lines on the claimed article are to represent conventional stitching.
